NIPPLE

Yervant H. Kurkjian, Paterson, N. J.

Application April 28, 1933, Serial No. 668,436

6 Claims. (Cl. 128—252)

This invention relates to nursing bottle nipples and has for its object the production of a simple and efficient nipple having a plurality of bottle neck gripping jaws which may be flexed to permit the placing of the nipple over the neck of a bottle with a minimum amount of effort, and which will efficiently grip the neck of the bottle after once having been placed thereover in such a manner as to prevent the nipple from becoming accidentally detached from the bottle neck.

Another object of this invention is the production of a simple and efficient nipple having a split bottle neck engaging skirt thereby providing a pair of flexible neck gripping jaws which will conform to the contour of the neck of the bottle and constitute an efficient securing means to prevent the accidental displacement of the nipple from the bottle neck.

A further object of this invention is the production of a nursing bottle nipple having a plurality of flexible jaws which provide the nipple skirt, the jaws being provided with beads at their extremities to constitute abutments against which the fingers may contact when placing the nipple over the neck of the bottle to insure an efficient and tight grip by the operator.

A still further object of this invention is the production of a simple nipple of the character described having a split skirt and a reinforcing bead extending around the edges of the split skirt to prevent the tearing of the skirt while placing the nipple over the neck of the bottle.

With these and other objects in view, this invention consists of certain novel constructions, combinations and arrangements of parts as will be hereinafter fully described and claimed.

In the drawing:

Figure 1 is a side elevation of a portion of a bottle showing the manner of applying the nipple thereto;

Figure 2 is a side elevation of a portion of a bottle showing the nipple mounted thereon, a portion of the nipple being shown in section;

Figure 3 is a section taken on line 3—3 of Figure 2;

Figure 4 is a side elevation of a modified form of the invention;

Figure 5 is a side elevation of a still further modified form; and

Figure 6 is a side elevation of a bottle cap embodying the same principle of the invention as disclosed in the present application.

Figure 7 is a sectional view taken on line 7—7 of Figure 2;

Figure 8 is a vertical sectional view taken on line 8—8 of Figure 5.

By referring to the drawing, it will be seen that 1 designates the bottle which is provided with the usual reduced neck portion 2 having a bead 5 of the conventional type.

The particularly constructed nipple 4 used in connection with the bottle 1 is provided with a depending skirt 5 which skirt 5 is provided upon each side with a longitudinally extending key-hole slot 6 terminating at its inner end in an enlarged preferably circular socket 7, which sockets 7 are spaced from the bead portion 21 of the nipple to provide a broad flat contracting neck-gripping band 24 between the bead 23 and the 10 sockets 7 due to the fact that the skirt 5 is of elastic material. This structure will divide the skirt 5 into a pair of flexible jaws 8 which may be flexed apart, as shown in Figure 1 when placing the nipple upon the bottle to facilitate the quick 15 application of the nipple to the neck of the bottle and prevent the nipple from slipping from the neck of the bottle while it is being applied thereto. As shown, particularly in Figures 1 and 2, a bead 9 is formed around the lower edge of the skirt 5 20 and this bead also continues around the edges of the slots 6 and the edges of the sockets 7 which are formed at the inner ends of the slots 6. These sockets 7 will facilitate the spreading of 25 the jaws apart when applying the nipple to the bottle and the shape of this enlarged socket, as well as the reinforcing bead which extends around the sockets as well as along the edges of the slots and the lower edge of the skirt will prevent the skirt from being torn or split when the 30 jaws are flexed or pulled apart as would be the case when applying the nipple to the bottle, as 35 illustrated in Figure 1. This structure provides not only a means for preventing the tearing or ripping of the skirt of the nipple but also greatly 40 reinforces the skirt and tends to cause the skirt to encircle and snugly fit around the neck of the bottle and adhere to the contour thereof, as soon as the jaws are released. The bead 9 which extends around the lower edge of the skirt will also 45 constitute an efficient means in the nature of an abutment for contacting with the finger which partly encircles the neck of the bottle when applying the nipple to the bottle and prevent the pull upon the nipple from slipping the nipple out 50 of engagement with this gripping finger of the operator. The rib or bead upon the opposite jaw which is gripped between the forefinger and thumb of the right hand, as illustrated, will also add an additional gripping medium to prevent the 55

slipping of the jaw from between the fingers as would be likely to happen if these hands were not provided due to the fact that the hands of the operator very often are slippery or moist from the milk which has just been placed in the bottle. The present invention is applicable both to the molded as well as the dipped type nipple. Figures 1, 2, 3, and 6 illustrate particularly the molded type, whereas Figures 4 and 5 illustrate the dipped type.

The skirt 5 may be provided with longitudinally extending reinforcing or stiffening spring or elastic ribs 23, if desired, to cause the jaws to be more firmly forced against the neck of the bottle.

From the foregoing description it will be seen that it is highly important therefore that the jaws not only constitute an efficient means for anchoring the nipple in position while first applying the nipple to the bottle and provide gripping means for the thumb and forefinger to complete the operation to place the nipple upon the bottle, but the jaws by being constructed and forming a definite part of the skirt and not merely an extension thereof, will provide means

for immediately snapping around the neck of the bottle and conform to the contour thereof. These jaws 8 are therefore essentially concavo-convex in cross-section since they are constructed from the substantially tubular skirt and form a definite part of the skirt, the jaws only being separated through the medium of the longitudinally extending comparatively narrow oppositely disposed slots formed in the sides of the skirt 5.

The skirt 5 may be provided with a suitable shoulder 10 which is conventional to the trade, formed upon the inner face of the skirt, and this shoulder may be of any suitable or desired character.

In Figure 4 there is shown a modified form of my invention wherein a nipple 11 is provided having a depending tubular skirt 12, this skirt 12 being also provided with longitudinally extending key-hole slots 13, each slot terminating at its inner end in an enlarged socket 14 similar to that described in Figure 2. The sockets 14 terminate short of the bead portion 25 to provide a broad flat contracting bottle neck-gripping band 26 located between the bead 25 and the sockets 14. In this form shown in Figure 4, a bead 15 is formed only around the lower edge of the skirt 12. The slots 13 will divide the skirt 12 into a pair of flexible substantially concavo-convex bottle gripping jaws 16.

In Figure 5 there is shown a further modified form of the invention wherein the nipple 17 is provided with a depending slit skirt 18, this slit skirt 18 constituting a pair of substantially concavo-convex bottle gripping jaws 19. These jaws are provided through the medium of the longitudinally extending key-hole slots 20. The structure shown in Figure 5 is that type of nipple which is known in the trade as the "Black Band Nipple" without the lower bead as illustrated either in Figures 2 or 4.

As is shown in Figure 6, the same structure described may be employed for producing a cap by providing a skirt which is longitudinally slotted in the manner described and illustrated similar to that shown in Figure 1.

In applying the nipple to a bottle, the forefinger of the left hand as shown in Figure 1 is placed in contact with one of the jaws 8 to abut against the lower bead 9 and this jaw is placed against the side of the neck of the bottle. The other jaw 8 is gripped between the thumb and

forefinger of the other hand and the jaws are pulled apart and the nipple is then flexed over the bead 3 of the bottle whereupon the rolled portion 21 of the nipple will snap over the bead 3 of the bottle and upon the release of the jaws 8 their flexibility will cause the skirt and jaws to snap closely against the sides of the bottle and will assist in holding the nipple in position. The wide flat contracting bottle neck-gripping band located below the bead portion of the nipple, in conjunction with the jaws of the skirt portion of the nipple will constitute an efficient means for firmly holding the skirt portion in contact with the neck of the bottle and cause the jaws and skirt portion to snugly fit against the bottle and prevent the edges of the jaws from being spaced from the neck of the bottle which would permit a baby to get its fingers under the jaws and by pulling upon the jaws away from the neck of the bottle, detach the nipple from the bottle.

The jaws 8 may, if desired, be provided with vacuum cups upon their inner faces in order to more effectively grip the neck of the bottle.

It should be understood that certain detail changes in the mechanical construction may be employed without departing from the spirit of the invention so long as these changes fall within the scope of the appended claims.

Having described the invention, what is claimed as new is:—

1. A device of the class described including a depending skirt of flexible elastic material, longitudinally extending slots being formed in the skirt from its lower end and terminating short of the upper end of the skirt to provide gripping jaws and a wide flat elastic expanding and contracting bottle neck-gripping band between the inner ends of the slots and the upper end of the skirt.

2. A nipple of the class described including an elongated elastic skirt of flexible elastic material terminating at its upper end in an outstanding bead portion defining an internal channel, said skirt having longitudinally extending slots leading from its lower end and terminating short of the bead portion to provide a wide elastic flat contracting bottle neck gripping band directly between the bead portion and the upper ends of the slots, the flat band being adapted to fit under the bead of a bottle neck about which the bead of the skirt fits and assist in holding the nipple upon the bottle, the slots in the skirt defining substantially concavo-convex elastic bottle-gripping jaws which extend substantially entirely about a bottle neck and are adapted to snugly adhere to the sides of a bottle neck to prevent the pulling of the jaws away from the neck of the bottle by the fingers of a baby using the nipple.

3. A nipple of the class described comprising an elastic body having an elastic skirt portion depending therefrom, said skirt portion having longitudinally extending slots leading from its lower end and terminating short of the upper end of the skirt portion to provide a wide neck-gripping band between the upper ends of the slots and the upper end of the skirt, the slots in said skirt portion defining jaws which are semi-circular in cross section and extend substantially the entire circumference of the skirt for snugly fitting about and gripping the neck of a bottle when the nipple is applied to a bottle, the inner faces of the jaws extending flush with the inner face of the skirt portion throughout the longitudinal length of the

skirt and being formed with suction cups to firmly hold the jaws against the bottle.

4. A nipple of the class described including a skirt portion of flexible elastic material having longitudinally extending slots leading from its lower end and terminating short of the upper end of the skirt portion, reinforcing beads formed around the lower end of the skirt portion and along the edges of said slots for preventing the splitting of the skirt above the slots when the jaws are spread apart for placing the nipple upon or removing the nipple from a bottle neck, said slots in said skirt defining substantially semi-circular jaws in cross section to extend substantially entirely about the bottle neck, the skirt and jaws being formed of flexible contracting elastic material whereby the jaws are adapted to snugly adhere to and grip around the neck of a bottle upon which the nipple is placed, and spring elastic ribs formed longitudinally of the skirt between the slots to assist in snapping the jaws snugly in contact with the neck of a bottle upon which the nipple is adapted to be placed.

5. A nipple comprising a body and a skirt portion depending therefrom and formed of flexible elastic material, said skirt being formed with slits leading from its lower edge and terminating in spaced relation to its upper end to provide an

unbroken upper portion for the skirt and circumferentially curved jaws of its lower portion having their side edges in close proximity to each other, whereby the said jaws will extend substantially entirely about a bottle neck and of their own resiliency have gripping engagement therewith, and an outstanding integrally formed bead extending along edges of the jaws to reinforce the jaws and impart added resiliency thereto.

6. A nipple comprising a body and a skirt portion depending therefrom and formed of flexible elastic material, said skirt being formed with slits leading from its lower edge and terminating in spaced relation to its upper end to provide an unbroken upper portion for the skirt and circumferentially curved jaws of its lower portion having their side edges in close proximity to each other, whereby the said jaws will extend substantially entirely about a bottle neck and of their own resiliency have gripping engagement therewith, and outstanding ribs formed integral with and extending longitudinally of the skirt between upper and lower edges thereof and disposed intermediate the side edges of the jaws for reinforcing the skirt and imparting added resiliency to the jaws.
